UNITED STATES PATENT OFFICE.

HENRY DIXON AND BRECKON DIXON, OF NOTTAWASAGA, COUNTY OF SIMCOE, ONTARIO, CANADA.

MACHINE FOR DRIVING FENCE-POSTS.

SPECIFICATION forming part of Letters Patent No. 281,848, dated July 24, 1883.

Application filed February 5, 1883. (No model.)

To all whom it may concern:

Be it known that we, HENRY DIXON and BRECKON DIXON, both subjects of the Queen of Great Britain, residing at the township of 5 Nottawasaga, in the county of Simcoe, in the Province of Ontario, Dominion of Canada, have invented a certain new and useful Machine for Driving Fence-Posts, of which the following is a specification.

10 The object of the invention is to provide a cheaply-constructed and effectively-operating machine for driving fence-posts; and the novelty consists in the construction and arrangement of parts, as will be more fully hereinafter set forth, and specifically pointed out in 15 the claim.

In the drawings, Figure 1 is a perspective view of our post-driving machine. Fig. 2 is a detail showing the flexible connection between the guide-frame and the bracing-frame.

20 A are two horizontal side timbers braced together by the cross-timbers B and C.

D are the rear wheels, properly journaled on short axles not extending across the machine.

25 E are the front wheels, properly journaled on the front axle, F, to which the tongue G is secured.

H are two timbers extending from the opposite end of the timber B in a backwardly and inwardly slanting direction to a point vertically, or nearly so, above the central point relatively to the wheels, where they meet and are rigidly secured together.

30 I are bracing-timbers extending from the rear ends of the timbers A to a point near the top end of the timbers H, which they are designed to brace and support in the position shown.

40 J is a guiding-frame composed of two timbers parallel to each other and rigidly braced together.

45 a is an eyebolt rigidly fastened to the guiding-frame J at or about its center. This eyebolt a is fitted to and hung upon the hook b, which passes through a block or blocks, d, attached to the top end of the frame formed by the two timbers H, as shown in Fig. 2. By thus flexibly connecting the guiding-frame J 50 to the timbers H the angle of the guiding-

frame may be adjusted, as will be hereinafter explained.

K is a cross-timber having longitudinal slots e cut in it at either end, through which the bolts L pass. These bolts also pass through 55 slots f, made in the side timbers, A.

A nut, L', with a lever attached for operating it, is provided with each bolt L, for the purpose of clamping the timber K in any desired position.

60 M is a forked foot rigidly bolted to the bottom of the frame J, and passing through slotted passage-ways made in the center of the timber K. This forked foot works loosely in the passage-ways cut for its reception through the 65 cross-timbers K, and is not intended to carry any portion of the weight of the frame J, merely acting as a guide for the said frame, the inclination of which can thereby readily be adjusted by the movement of the cross-timer K.

70 N is a metal block of any suitable weight, and provided with guides which fit over the guiding-frame J, as shown. This block has thereby free vertical movement upon the guiding-frame J, but has no lateral motion thereon.

O is a sliding cross-head attached to and sliding upon the guiding-frame J.

75 P is a pair of tongs pivoted upon the cross-head O, and having hooked ends to fit over the V-shaped head n, formed upon or attached to the block N. An ordinary spring or springs are employed to act with a constant force to hold the hooked ends of the said fork together.

80 g are two pins projecting from the face of the guiding-frame J at its top end. These pins are intended to come in contact with and open the tongs P when the said tongs are raised to the top of the frame J by the rope or chain 90 Q, which passes over suitable pulleys in the frame, as shown.

85 R is a support suitably pivoted to the frame J, and having a notched end, into which the bottom edge of the block N fits when it is desired to support the said block, while the post to be driven is being adjusted below it.

95 Having now described the general construction of our fence-post-driving machine, we shall now proceed to explain its operation.

100

Instead of digging holes when about to erect a fence, we sharpen slightly one end of the post, and, driving our machine on the line of the fence, place the post against the guiding-frame 5 J. This guiding-frame being adjustable on the horizontal frame, which rests on the ground, it is set so as to be perpendicular, in order that the blow of the falling block N will drive the post straight into the ground. Having adjusted 10 the frame J, by moving the cross-timber K, so that the said frame J shall be exactly perpendicular, we tighten the clamping-nuts L. Having permitted the cross-head O to descend, so that the spring-tongs P shall grasp the V-shaped head attached to the weight or block 15 N, we draw upon the rope Q until the cross-head O reaches the top of the frame J, when the legs of the tongs P come in contact with the pins g, opening the said tongs and releasing them from the block N, which immediately 20 falls from its elevated position onto the post below it. As shown in the drawings, the block has just fallen from the tongs. It will be seen that this operation can be repeated with great 25 rapidity, a horse being preferably used for the purpose of raising the weight. As each post is driven into the ground as far as required, the machine is drawn to the next point where it is desired to drive a post, and the operation repeated. The portability of our post-driving 30

machine will be found a great advantage; but the great feature of the invention is the facility with which the frame on which the weight slides can be adjusted so as to maintain a perpendicular position, notwithstanding the unevenness 35 of the ground over which the machine is drawn.

We are aware of Patent No. 20,563, of 1858, in which a guide-frame works in a sextant, and is adjustable by universal joint and suspended from above. Such construction is not sought 40 to be covered in this application.

What we claim as new is—

In a machine for driving fence-posts, and in combination with a carriage-frame having longitudinal slots, and a supporting-frame having a suspending-hook, a guide-frame adapted to carry the block suspended from said hook, and having a transverse bar provided with longitudinal slots arranged at approximate right angles to the slots in the carriage-frame, 45 and means, as L L, for securing the said transverse bar and carriage-frame together when the guide-frame has assumed a vertical position, as set forth.

HENRY DIXON.
BRECKON DIXON.
